H. J. JOERDEN.
ENGINE STARTER.
APPLICATION FILED AUG. 2, 1915.

1,190,174.

Patented July 4, 1916.

UNITED STATES PATENT OFFICE.

HARRY J. JOERDEN, OF LOS ANGELES, CALIFORNIA, ASSIGNOR OF ONE-FIFTH TO
LAMONT S. WREN, OF HAWTHORNE, CALIFORNIA.

ENGINE-STARTER.

1,190,174.

Specification of Letters Patent.

Patented July 4, 1916.

Application filed August 2, 1915. Serial No. 43,273.

To all whom it may concern:

Be it known that I, HARRY J. JOERDEN, a citizen of the United States, residing at Los Angeles, in the county of Los Angeles and State of California, have invented new and useful Improvements in Engine-Starters, of which the following is a specification.

This invention relates to an engine starter, and pertains especially to a mechanical 10 starter for internal combustion engines.

It is an object of this invention to provide a starter having a power accumulator which, when fully charged, automatically disconnects the gearing between the power 15 accumulator and a source of power.

It is another object of this invention to provide a starter in which the gearing connecting a power accumulator and a source of power will be thrown out of engagement, 20 the starter thrown into engagement with the crank shaft of the engine to be started, and a brake released, thereby supplying the power for turning over the engine.

A further object of my invention is to 25 provide a winding mechanism for a mechanical starter, which is operated by the vibrator of the vehicle body with respect to the frame.

Embodiments of my invention are illustrated in the accompanying drawing, in 30 which:

Figure 1 is an elevation partly in section of a preferred form of my starter. Fig. 2 is a side elevation of a detail. Fig. 3 is a 35 side elevation showing the brake mechanism. Fig. 4 is a section as seen on the line 4—4 of Fig. 1. Fig. 5 is a modified form of the winding mechanism.

Referring to Figs. 1, 2, 3 and 4, a frame 40 is indicated at 6 provided with a bearing 7 for a shaft at one end of the frame, and a bearing 8 at the opposite end. Frame 6 is provided with a track 9' extending longitudinally of the frame and adjacent the bearing 8. Rotatably mounted in the bearings 7 and 8 is a shaft 9 which is provided with a longitudinal groove 10 adapted to receive sliding rods. Fixedly secured to the shaft 9 is a brake drum 11 suitable for a 45 brake band 12, the latter being of the usual type. Brake band 12 is secured at one end to a bracket 13, and at the other end to a lever 14 of the bell crank form, and is pivotally mounted upon the frame 6 as indicated at 15. A helical spring 16 holds the 55 brake band against the brake drum.

A bevel gear 17 is rotatably mounted upon the shaft 9. The hub 18 of the bevel gear is provided with a radial aperture which is counterbored, as indicated at 19 and receives 60 a cap 20. Mounted within cap 20 is a detent pin 21 which is pressed downwardly by a helical spring 22, thereby providing means for clutching the bevel gear 17 to the shaft 9. Fixedly mounted upon the shaft 9 is a 65 spur gear 23 adapted for transmitting power to the internal combustion engine shaft.

Secured to the shaft 9 adjacent the spur gear 23 is a spiral spring 24 which serves as a power accumulator. Upon the outer convolution of the spiral spring 24 a striker 25 is mounted in a position such that it may engage a trigger. An over-hanging arm 26 is mounted upon the frame preferably integral therewith, and pivotally mounted upon it is a trigger 27 so balanced that the right hand end normally will extend downward by its own weight. Shaft 9 has adjacent one end thereof a helical flange 28 forming a screw thread. Mounted upon the shaft 9 70 is a ring member 29 which is internally grooved or threaded and adapted to engage with the thread 28. Instead of the flange 28, shaft 9 may be provided with a helical groove and ring member 29 provided with 75 a flange. Ring member 29 has a depending lug 30 which is grooved along its lower side as indicated at 31, and so disposed that the shaft 9 is received within the groove. A helical spring 32 abuts the bearing 8 and a 80 shoulder on the ring member 29 tending to force the ring member into engagement with the threads 28.

A pinion 33 is slidably mounted upon a shaft 34 and so disposed that it may be engaged with the spur gear 23. Shaft 34 is shown as an extension of the crank shaft of the engine. A collar 35 is rotatably mounted upon a member 36 which is secured to the pinion 33. Secured to the collar 35 is a 95 link arm 37, thereby providing means for sliding the pinion 33 on the shaft 34 into and out of mesh with the spur gear 23. A lever 38 is pivotally connected to link 37. A helical spring 39 normally retracts the 100 lever 38 and the link 37, holding pinion 33 in a position out of mesh with spur gear 23. Lever 38 is so positioned that when it is

moved to the right, it will abut lever 14. A guide pin 40 is disposed upon lever 14 and passes through an aperture in lever 38, thereby guiding the latter. It will be noted that there is a lost motion between lever 38 and lever 14. Secured to lever 38 is a rod 41 which is disposed in the groove 10 of shaft 9 and is adapted to slide longitudinally. The inner end of rod 41 is beveled 10 as indicated at 42, so that as the rod is forced inward the detent pin 22 will be pushed upward, unclutching the gear 17 from the shaft 9.

Oppositely disposed to rod 41 and mounted in the groove 10, is a slidable rod 43 provided at its inner end with a bevel portion 44 adapted to engage the detent pin 22 and unclutch the gear 17 from the shaft. Rod 43 is provided with an outwardly extending portion 44' which rides in a groove on ring member 29 so that it may rotate with respect to the ring member, but is retained against longitudinal movement with respect to the ring member.

In mesh with the bevel gear 17 is a bevel pinion 45 mounted upon a shaft 46, which is journaled in a bearing 47 on the frame 6 and has a helical flange forming a screw thread. Frame 6 is adapted to be secured to the body of an automobile. A beam 48 of I-form is secured to the frame of the automobile. Mounted upon beam 48 is a casing 49 having outwardly extending legs 50 and 51 at the lower end adapted to be engaged by yokes 52 and 53 which are threaded at the ends for the reception of nuts. The threaded ends of the yokes are extended through apertures in the I-beam engaging legs 50 and 51 by which means the casing 49 is secured to the beam 48. At the upper end of casing 49 is secured a housing 54 within which is mounted a collar 55 provided on its periphery with ratchet teeth. A cap plate 56 is secured upon the upper end of housing 54 by means of screws or any other suitable securing means. A pawl 57 is mounted in the housing for engagement with the ratchet teeth on collar 55. Collar 55 is internally grooved or threaded 50 and engages the threads on shaft 46. The shaft 46 may be grooved instead of being threaded and collar 55 provided with a flange which engages the groove. It is understood that the term threaded as hereafter used includes either flange or a groove on the shafts.

The operation of my starter is as follows: As the vehicle travels the vibration between the frame and the body of the vehicle causes a reciprocation of shaft 46. As the shaft moves in one direction, pawl 57 permits the collar 55 to rotate, but as the shaft 46 moves in the opposite direction the pawl 57 prevents rotation of the collar 55 and results in causing rotation of shaft 46 due to

the engagement of the threads on collar 55 and the threads on shaft 46. This causes a rotation of pinion 45 and a consequent rotation of pinion 17.

Assuming that the detent is in the groove 10 of shaft 9, the shaft 9 is rotated and the spring 24 wound. As the spring 24 contacts the striker 25 engages trigger 27 and releases ring member 29. Spring 32 forces ring member 29 into engagement with the thread 28. As ring member 29 is prevented from rotating by rail 9' the ring member rides longitudinally along the shaft 9, moving the rod 43 and raising detent pin 21, and disengaging the gear 17. The starter is now in condition for supplying power and turning over the crank shaft of the engine.

Assuming that the engine is not in operation, and that spring 24 is wound, lever 38 which may be operated by a hand lever 85 or foot treadle is pulled to the right throwing pinion 33 into mesh with spur gear 23, moving lever 14 in opposition to spring 58, and releasing the brake band 12, permitting the spring 24 to rotate the shaft 9. The rotation of the shaft causes ring member 29 to ride to its outward position, whereupon the trigger 27 engages the ring member 29 and holds it out of engagement with thread 28. At the same time rod 41 is moved to the right, and lifts the detent pin 22 maintaining the bevel gear unclutched from the shaft 9. The spring 24 rotating the shaft, turns the engine over and starts it. Upon release of the lever 38 spring 39 retracts it throwing pinion 33 out of mesh with spur gear 23, moving rod 41 out of engagement with the detent pin 21, whereupon the spring 22 forces the detent pin into the slot 10 and clutches the bevel gear 17 to the shaft. Spring 58 pulls lever 14 and tightens the brake band 12, preventing rotation of the brake drum 11 in a direction counter to the large arrow shown in Fig. 3, this being the direction in which the spring unwinds. Vibration of the vehicle in its movement will cause gear 17 to be rotated. The brake band 12 on brake member 11 is permitted by reason of the springs 16 and 58 to loosen sufficient for the winding operation. The spring 115 is now wound as before described.

In Fig. 5 I have shown means for winding the spring from the crank shaft to the engine. Gear 123 corresponds to gear 23 in Fig. 1. Pinion 133 corresponds to pinion 33 in Fig. 1. Gear 58 is rotatably mounted upon the shaft and has the detent mechanism 59 of construction similar to the one shown in Fig. 1. An idler gear 60 is disposed so that the pinion 133 may mesh therewith when out of mesh with pinion 123. Pinion 133 is connected to linkage for operating the brake band and throwing the detent out of operation. The mechanism is otherwise like that shown in Fig. 1.

It is within the scope of my invention to wind the spring manually or by any other means. It will be obvious that I have provided a starting mechanism suitable for automobiles, or one which may be used upon any internal combustion engine especially those of small horse power.

What I claim is:

1. A starter, comprising in combination a shaft; mechanism for operatively engaging the said shaft with the crank shaft of an internal combustion engine, but normally out of engagement therewith; a brake mechanism normally holding said shaft against rotation in one direction, but permitting rotation in the opposite direction; mechanism connecting a source of power to said crank shaft; a clutch normally engaging said last named mechanism with said shaft; a power accumulator operatively secured to said shaft; means operated by said power accumulator to release said clutch when said power accumulator is charged; and mechanism for simultaneously releasing said clutch, said brake mechanism and operatively engaging the first named mechanism with said shaft.

2. A starter comprising a shaft; a gear secured thereto; means for operatively engaging the gear with the crank shaft of an internal combustion engine; a brake secured to said shaft normally holding the shaft against rotation in one direction, but permitting rotation of the shaft in the opposite direction; a gear mounted on said shaft; a source of power geared to the last named gear; a clutch for engaging said last named gear with the shaft; a power accumulator secured to said shaft; means connected to said power accumulator to throw said clutch out of engagement, when said power accumulator has been fully charged; mechanism for throwing said clutch out of engagement, releasing said brake, and operatively engaging the first named gear.

3. A starter comprising a shaft provided with a longitudinal groove; mechanism for operatively engaging said shaft with the crank shaft of an internal combustion engine, but normally out of engagement therewith; a brake mechanism normally holding said shaft against rotation in one direction, but permitting rotation of the shaft in the opposite direction; a gear mounted on said shaft; a source of power in mesh with said gear; a dog on said gear normally disposed in the groove on said shaft; a power accumulator secured to said shaft; a sliding rod disposed in the groove of said shaft for engagement with said dog; mechanism secured to said rod for sliding the latter to move said dog out of engagement with said shaft; means operated by said power accumulator for controlling the last named mechanism; a second sliding rod disposed

in the groove on said shaft for moving said dog out of engagement with said shaft; and means for moving the last named rod to release said dog, release said brake, and engage said shaft with said crank shaft.

4. A starter comprising a shaft provided with a longitudinal groove and a thread thereon disposed adjacent one end thereof; mechanism for operatively engaging said shaft with the crank shaft of an internal combustion engine, but normally out of engagement therewith; a brake mechanism normally holding said shaft against rotation in one direction, but permitting rotation of the shaft in the opposite direction; a gear mounted on said shaft; a source of power in mesh with said gear; a dog on said gear normally disposed in the groove on said shaft; a power accumulator operatively secured to said shaft; a sliding rod disposed in the groove of said shaft for engagement with said dog, an internally threaded member mounted on said shaft for engagement with the thread on said shaft, normally contiguous to said thread and provided with means preventing rotation thereof; resilient means tending to force said internally threaded member into engagement with the thread on said shaft; a catch disposed to hold said internally threaded member out of engagement with said thread; means operated by said power accumulator when charged to release said catch; a second sliding rod disposed in the groove on said shaft for moving said dog out of engagement with said shaft; and means for moving the last named rod to release said dog, release said brake, and engage said shaft with said crank shaft.

5. A starter comprising a shaft, provided with a longitudinal groove and a thread adjacent one end thereof, mechanism for operatively engaging said shaft with the crank shaft of an internal combustion engine, but normally out of engagement therewith; a brake mechanism normally holding said shaft against rotation in one direction, but permitting rotation of the shaft in the opposite direction; a gear mounted on said shaft; a source of power in mesh with said gear, a dog on said gear normally disposed in the groove of said shaft; a motor spring secured to said shaft; a sliding rod disposed in the groove of said shaft for engagement with said dog; an internally threaded member for engagement with the thread on said shaft mounted on said shaft normally contiguous to said thread and provided with means preventing rotation; resilient means tending to force said internally threaded member into engagement with said thread; a trigger disposed to hold said internally threaded member out of engagement with said thread; a striker secured to said spring for engaging said trigger; a second sliding rod disposed

in the groove on said shaft for moving said dog out of engagement with said shaft; and means for moving the last named rod to release said dog, release said brake, and engage said shaft with said crank shaft.

6. A starter comprising a shaft; mechanism operatively engaging said shaft with the crank shaft of an internal combustion engine, but normally out of engagement therewith; a brake mechanism normally holding said shaft against rotation in one direction, but permitting rotation in the opposite direction; winding gearing secured to said shaft comprising a threaded shaft; an internally threaded ring member on said threaded shaft; intermittent grip means in engagement with said ring member; means rotatively supporting said ring member and said intermittent grip means adapted to be secured to the vibrating part of a vehicle; a clutch for engaging said gearing with said shaft; a power accumulator operatively secured to said shaft; means operated by said power accumulator to release said clutch when said power accumulator is charged; and mechanism for releasing said clutch, said brake mechanism, and operatively engaging the first named mechanism with said shaft.

7. A starter comprising a shaft; mechanism for operatively engaging said shaft with the crank shaft of an internal combustion engine, but normally out of engagement therewith; a brake mechanism normally holding said shaft against rotation in one direction, but permitting rotation in the opposite direction; winding gearing secured to said shaft comprising a threaded shaft; an internally threaded ring member on said threaded shaft; said threaded member provided with ratchet teeth on its periphery; a pawl in engagement with said ratchet teeth; means rotatively supporting said link member and said pawl and adapted to be secured to the vibrating part of a vehicle; a clutch for engaging said gearing with said shaft; a power accumulator operatively secured to said shaft; means operated by said power accumulator to release said clutch when said power accumulator is charged; and mechanism for releasing said clutch, said brake mechanism, and operatively engaging the first named mechanism with said shaft.

In witness that I claim the foregoing I have hereunto subscribed my name this 17th day of July, 1915.

HARRY J. JOERDEN.
